CLAIM

I claim the ornamental design for a misting fan, as shown and described.

DESCRIPTION

FIG. 1 is a perspective view of the misting fan according to the present design;

FIG. 2 is a front plan view of the present design;

FIG. 3 is a right side view of the present design, a corresponding left side view being a mirror image thereof;

FIG. 4 is a rear plan view of the present design;

FIG. 5 is a bottom plan view of the present design; and,

FIG. 6 is a top view of the present design.
